TELEVISION SYSTEM

Robert E. Shelby, Teaneck, N. J., assignor to Radio Corporation of America, a corporation of Delaware

Application January 14, 1938, Serial No. 184,912

4 Claims. (Cl. 178—7.2)

This invention relates to an improvement in television systems.

More specifically the present invention relates to an improvement in systems used for transmitting pictures by television in which a cathode ray transmitting tube is used to transfer the visual image that is to be televised into a series of electrical signals. Such a tube is commonly known as an "Iconoscope" and is provided with a mosaic electrode comprising a plurality of discrete photo-electric elements and a cathode ray generating and deflecting means for scanning the mosaic to produce a series of electrical signals from the separate charges on the individual photo-electric elements of the mosaic. The signals derived from the television transmitting tube are then amplified and modulated for subsequent broadcast. An example of the construction of the mosaic electrode is clearly shown and described in the patents to S. F. Essig #2,062,122 of November 24, 1936, and #2,065,570 of December 29, 1936.

In the use of systems employing such a transmitting tube it has not been uncommon to find superimposed upon the series of picture signals alternating current components of the same frequencies as the line and frame deflecting frequencies which are impressed upon the deflecting means for the cathode ray beam. It is believed that this superimposition of the line and frame frequencies upon the series of picture signals is because of an electrostatic condition which exists between the beam deflecting unit and the mosaic electrode or signal plate.

Also, in the use of such a television transmitting system, it has been found that the distributed capacity between the "Iconoscope" or television pick-up tube and ground, as well as the distributed capacity between the output circuit of the television pick-up tube and ground, has, in some instances, caused a certain degree of attenuation and distortion of the series of picture signals with the result that the reproduced image on the television receiver is not as clear in detail as might be if these distributed capacities were eliminated.

It is, therefore, one purpose of the present invention to provide means whereby the presence of impulses of line and frame frequency which are superimposed upon the series of picture signals because of electrostatic conditions existing between the deflecting means and the mosaic electrode may be eliminated.

Another purpose of the present invention resides in the provision of means whereby the electrostatic field which exists between the deflecting

means and the mosaic electrode or plate may be compensated for regardless of whether electrostatic or electromagnetic deflection (or a combination of these) is used.

A still further purpose of the present invention resides in the provision of means whereby the second anode of the television pick-up tube or "Iconoscope" may be operated at a positive potential with respect to ground in order that an impedance or impedance network may be connected between the second anode and ground potential or between the second anode and a source of potential less positive than the potential of the second anode, for the purpose of eliminating or counteracting the effect of electrostatic condition which exists between the deflecting anode and the mosaic electrode or plate.

A still further purpose of the present invention resides in the provision of means whereby the television pick-up or transmitter tube as well as the output circuit for the tube may be shielded in order to reduce the effect of the inherent distributed capacity between these elements and ground.

A still further purpose of the present invention resides in the provision of means whereby the picture signals derived from the television pick-up tube may be applied to a first video amplifier and means whereby signals from this amplifier may be transferred to additional amplifier stages by way of a cathode resistance; that is, by a cathode coupling.

A still further purpose of the present invention resides in the provision of means whereby the shield member which surrounds the television pick-up tube and output circuit therefor may be connected to the cathode of the first video amplifier tube.

A still further purpose of the present invention resides in the provision of means whereby the potential of the second anode with respect to ground and the potential of the shield of the television pick-up tube and output circuit with respect to ground may be at substantially the same potential.

Other purposes and advantages of the present invention will become more apparent to those skilled in the art from a reading of the following specification and claims, particularly in connection with the drawing, wherein the single figure illustrates one form of the present invention.

Referring more particularly to the drawing, a television pick-up tube or "Iconoscope" is shown generally at 10. The tube comprises a glass envelope which encloses a mosaic electrode 12 consisting of a large number of discrete photo-elec-

tric elements and a signal plate 14 to which an output circuit may be connected. The image to be televised is focused upon the mosaic 12 by means of an appropriate lens system 30.

5 For the purpose of scanning the mosaic in order to remove the potentials which exist on the separate photo-electric elements thereof in accordance with the light image projected thereon, a cathode ray gun structure is provided comprising a cathode 16, which may be heated by any appropriate means such as by an electrically operated heater. A grid structure 18 is also provided for controlling the intensity of the electrons which are emitted by the electron emitter 16, and 10 a first anode 20 is provided for properly accelerating the electrons in the direction of the mosaic electrode 12. For further accelerating the electrons and for focusing the same into a narrow beam, a second anode 22 is provided which extends from a region adjacent the first anode to the interior of the television pick-up tube proper. The manner in which a cathode ray may be focused to a small elementary area is described and discussed in the patent to P. E. L. Chevallier 15 #2,021,252 and #2,021,253 of November 19, 1935, as well as in the patent to R. H. George #2,086,546 of July 13, 1937. This second anode also performs the function of attracting the secondary electrons and photo-electrons which may be 20 emitted from the mosaic 12.

For the purpose of deflecting the cathode ray beam a deflecting unit 24 is provided. This unit may consist of two pairs of deflecting coils so arranged that their fields are at right angles to each other and are each at right angles to the direction of travel of the cathode ray beam. By appropriately energizing the deflecting coils the cathode ray beam may be caused to systematically scan the surface of the mosaic plate. Conductors 30 for supplying energy to the deflecting coils are shown, and in order that the coils may be energized a current or voltage of appropriate wave form may be applied to the terminals 26 and 28. Instead of using electro-magnetic means for 35 causing deflection of the cathode ray beam, electrostatic means may be used in which case two pairs of plates are ordinarily provided, the pairs being arranged in planes at right angles to each other and parallel to, but spaced from the path 40 of the cathode ray beam in a manner which is well known in the art. By applying appropriate potentials to the deflecting plates an electrostatic field may be created between the pairs of plates with the result that the cathode ray beam 45 is deflected horizontally and vertically in order to properly scan the mosaic electrode.

A further and more specific discussion of the construction and operation of the cathode ray television transmitting tube is believed to be unnecessary since its operation is well known to those skilled in the art and since a clear and concise description of the operation of the tube may be had by referring, for example, to a patent to V. K. Zworykin #2,021,907 of November 26, 1935.

55 In order that appropriate potentials may be applied to the elements of the cathode ray gun a potentiometer 23 is provided, to the ends of which is to be connected a source of current. The first and second anodes are, of course, positive 60 with respect to the cathode whereas the grid of the gun structure is slightly negative with respect thereto. Some point along the potentiometer, preferably between the first and second anode terminals, is connected to ground as shown 65 in the drawing. An impedance member 34 is

provided, one end of which is connected to the second anode by conductor 32 and the other end of which is connected to a point along the potentiometer by conductor 33. Both the impedance connection and the ground connection to 5 the potentiometer are adjustable and may occupy identical positions on the potentiometer or may occupy separate and different positions. In order to provide a convenient path to ground for alternating current which may appear in the impedance circuit, a condenser 35 is provided and is connected between the conductor 33 and ground. This condenser must, of course, be of sufficient size to render little or substantially no impedance to the alternating currents which may be present 10 in the impedance 34.

The impedance member 34 preferably consists of a parallel arrangement of a resistance and a variable condenser. It is to be understood, however, that other impedance networks may be used 20 and that the value of the impedance network used may be so chosen as to properly compensate for signals which appear in the output circuit of the television pick-up tube as a result of the electrostatic condition which exists between 25 the deflecting unit 24 and the mosaic electrode 12.

Connected to the signal plate 14 of the mosaic electrode 12 is an output circuit 36 which conducts the picture signals to the control electrode of the first video amplifier tube 40. The anode of this 30 tube is connected to a terminal 48 to which may be applied a source of positive potential. The cathode and screen grid of the video amplifier tube 40 are connected to ground by way of a cathode resistance 46 and the control electrode of the 35 amplifier tube is biased to appropriate operating potential by means of the source of current 42. In the connection between the source of current 42 and the control electrode is a grid resistor 44.

When the signals from the signal plate 14 of 40 the television pick-up tube are applied to the control electrode of the video amplifier tube 40 a variation in the amount of current which is transmitted through the tube results. This variation in current causes a variation in potential drop 45 to appear across the cathode resistance 46 and this potential is used to supply power to the control electrodes of the succeeding stages of video amplification. The following stages of video amplification are therefore connected between the 50 terminal 50 and ground.

A certain distributed capacity is inherently present between the television pick-up tube 10 and ground, as well as between the output circuit 36 and ground. In order to compensate for this 55 distributed capacity which electrically appears as a condenser between the control electrode of the video amplifier 40 and ground, a shield member 38 is provided and this shield member is connected by way of a conductor 39 to the cathode 60 of the video amplifier tube 40.

In order for the secondary electrons and the photo-electrons which originate at the mosaic electrode to be attracted to the second anode to produce proper functioning of the television pick- 65 up tube, the second anode is preferably operated at a potential which is slightly positive with respect to ground. The amount of the potential is preferably equal to the positive potential of the mosaic signal plate 14 with respect to ground; 70 i. e., the potential of the grid bias source of potential 42.

As stated above, there appears a certain electrostatic condition between the deflecting unit 24 and the mosaic electrode 12 which may cause 75

alternating current components of line and frame frequency to be superimposed upon the picture signal. There also exists a certain electrostatic condition between the deflecting unit 24 and the second anode 22 and as a result alternating current components of line and frame frequency appear in the conductor 32. When the impedance 34 is introduced in the conductor 32, and properly adjusted to cause a phase shift or reversal of the 10 alternating current components appearing therein, the net effect is to cause a compensation for the corresponding alternating current components which may appear in the output circuit of the television pick-up tube. Any alternating currents of line and frame frequency which may appear in the output circuit of the television tube as a result of the electrostatic condition existing 15 between the deflecting unit 24 and the mosaic electrode 12 are thereby eliminated insofar as 20 their effect is concerned.

Since it is known that triodes as a class are in general better than screen grid tubes for low level stages of amplification because of lower noise relative to signal strength, it is desirable that triodes 25 be used in the video amplifier. However, in view of the fact that a triode normally has a relatively high effective input capacity it is not desirable to use a triode as the first input tube for video signal currents from a television pick-up tube.

30 Since it is known that the effective input capacity of a cathode coupled amplifier is lower than that of the same tube connected with output load in the anode circuit, a cathode coupled pentode is used to couple the television pick-up tube to the 35 following triode amplifying stages. If such an arrangement is to be entirely satisfactory and used to its best advantage, the cathode coupled stage must not contribute appreciably to the total noise if a satisfactory noise level is to be maintained. When the first video amplifier tube is 40 used in the manner shown in the drawing, the cathode coupled stage may be considered as an impedance transformer for coupling the "Iconoscope" to the first amplifier stage which follows. 45 In view of the fact that the inherent distributed capacity of the television pick-up tube and the picture signal output circuit to ground has been appreciably reduced, it is possible to increase the value of the resistance 44 and thereby increase 50 the amplification of the tube 40 as well as improve the signal to noise ratio.

The inclusion of the impedance 34 and its connection as shown in the drawing provides means whereby any alternating current signals of the 55 frequency of the line impulses or the frame impulses which appear in the output circuit of the television pick-up tube (and which are undesirable) may be eliminated and compensated for particularly when the impedance 34 is so arranged as to cause proper phase opposition relationship to exist between the alternating current potentials which are present there-across as a 60 result of the electrostatic condition, with respect to the phase relationship of the undesirable signals which appear in the grid circuit of the video amplifier tube 40.

From the above it may therefore be seen that an improved television system has been developed 70 wherein the signal to noise ratio has been increased by the substantial elimination of the distributed capacity between the cathode ray tube and ground as well as between the output circuit of the television pick-up tube and ground, and the further provision of means whereby undesirable superimposed alternating current impulses

which may appear upon the picture series signal as a result of the electrostatic condition existing between the deflecting unit and the mosaic electrode have been eliminated by means of cancellation.

It is to be understood that although various modifications and amendments may be made in the present invention, it is desired that any and all such modifications be considered within the purview of the present invention, except as limited by the hereinafter appended claims.

I claim:

1. A television system including a pick-up tube comprising an envelope, a photo-sensitive mosaic in said envelope, a signal plate capacitively associated with said mosaic, an electron gun structure in said tube including an electron emitter and an accelerating anode for developing and projecting a beam of electrons against said mosaic, means including a deflecting yoke for causing the beam of electrons to systematically scan said mosaic, at least a portion of said accelerating anode being positioned between the deflecting yoke and said signal plate, the relationship of the deflecting yoke, the accelerating anode and the signal plate being such that an inherent mutual capacity coupling exists therebetween, means connected to said electron emitter and to said anode to maintain the latter at a potential positive with respect to said emitter and to ground, an impedance network including a parallel resistance and condenser, and means to connect said impedance network between said anode and ground to substantially reverse the phase of the alternating current component of the current appearing in the accelerating anode circuit whereby the alternating current potential variations of the anode by reason of the capacity relationship between the deflecting yoke and the anode will be substantially out of phase with respect to the potential variations of the deflecting yoke to thereby compensate for the capacity effect between the deflecting yoke and the signal plate.

2. A television system including a pick-up tube comprising an envelope, a photo-sensitive mosaic in said envelope, a signal plate associated with said mosaic, an output circuit connected to said signal plate, an electro gun structure in said tube including an electron emitter and an accelerating anode for developing and projecting a beam of electrons against said mosaic, means including a deflecting yoke for causing the beam of electrons to systematically scan said mosaic to produce a series of signals in said output circuit, the relationship of the deflecting yoke, the accelerating anode and the signal plate being such that an inherent mutual capacity coupling exists therebetween, an impedance network including a resistance and a condenser connected in parallel, means for connecting said impedance network between said anode to ground to cause an alteration of the phase relationship of the alternating current voltage variations of the anode due to the proximity of the deflecting yoke and the capacity relationship between the deflecting yoke and the anode, and means to maintain said anode at a positive potential with respect to said electron emitter and with respect to ground whereby the presence of spurious signals of scanning frequency due to the capacity effect between the deflecting yoke and the signal plate are substantially eliminated from the output circuit.

3. A television system including a pick-up tube comprising an envelope, a photo-sensitive mosaic

in said envelope, a signal plate cooperatively associated with said mosaic, an electron gun structure in said tube including an electron emitter and an accelerating anode for developing and 5 projecting a beam of electrons against said mosaic, means including a deflecting yoke for causing the beam of electrons to systematically scan said mosaic, means for maintaining said anode at a potential positive with respect to 10 ground and for maintaining the electron emitter at a potential negative with respect to ground, the position of the deflecting yoke, the accelerating anode and the signal plate being such that a slight amount of capacity coupling exists there- 15 between, and a phase reversing impedance net- work, including a resistance and a condenser connected between said anode and ground for altering the phase relationship of the low amplitude alternating current voltage variations of the 20 anode as induced therein from the deflecting yoke due to the capacity relationship between the deflecting yoke and the anode to prevent the presence of spurious signals of line and frame frequency from appearing at the signal plate be- 25 cause of the presence of the deflecting yoke.

4. A television system including a pick-up tube

comprising an envelope, a photo-sensitive mosaic in said envelope, a signal plate associated with said mosaic, an electron gun structure in said tube including an electron emitter and an accelerating anode for developing and projecting a 5 beam of electrons against said mosaic, means including a deflecting unit for causing the beam of electrons to systematically scan said mosaic, the position of the deflecting anode, the accelerating unit and the signal plate being such that a slight 10 inherent mutual capacity coupling exists there- between, means including an impedance network comprising a resistance and a condenser for connecting said anode to ground in order to substan- tially reverse the phase of the alternating current 15 compoent of the current appearing in the accelerating anode circuit and to thereby substantially reverse the phase of the low amplitude alternating current voltage variations of the anode whereby the capacity effect between the deflect- 20 ing unit and the signal plate may be substan- tially nullified, and means to maintain said anode at a positive potential with respect to said elec- tron emitter and with respect to ground.
